United States Patent Office.

W. T. WYLIE, OF NEW CASTLE, PENNSYLVANIA.

Letters Patent No. 64,732, dated May 14, 1867.

IMPROVEMENT IN SHAVING-BRUSHES.

The Schedule referred to in these Letters Patent and making part of the same.

TO ALL WHOM IT MAY CONCERN:

Be it known that I, W. T. WYLIE, of New Castle, Lawrence county, Pennsylvania, have invented an Improvement in Brushes for Shaving and other purposes; and I do hereby declare the following to be a full, clear, and exact description of the same, reference being had to the accompanying drawing, and to the letters of reference marked thereon.

My invention consists of certain devices, fully described hereafter, combined with a brush with which is connected a reservoir containing the material to be distributed by the brush, the said devices facilitating the transfer of the material from the reservoir to the brush.

In order to enable others skilled in the art to make and use my invention, I will now proceed to describe its construction and operation. On reference to the accompanying drawing, which forms a part of this specification—

Figure 1 is an external view of a shaving-brush with my improvement.

Figures 2 and 3, sectional views, showing the parts in different positions; and

Figure 4 a section on the line 1 2, fig. 2.

The body A of the brush is hollow, and in the lower end of the same is secured, in any suitable manner, the usual mass of bristles or hairs B. Near the upper end of the mass of bristles B are inserted a number of small tubes *a a*, which communicate with the interior of the hollow body A, for a purpose described hereafter. Into the upper end of the body A screws the lower open end of a cylindrical metal casing C, and to the upper end of the latter is fitted a screw-cap, D. To the casing C is fitted a piston, E, on the rod *b* of which is cut a thread corresponding to that in a nut, F, the latter being so secured to the cap D that it can turn freely on without being detached from the same. At the upper side of the nut F is a projection, *e*, on to which screws a cap, G, of the form shown in the drawing, and at the lower end of the body A of the brush are threads adapted to those at the end of a cylindrical cap, H, which, when secured to the brush, encloses the bristles B. To prepare the brush for use the casing is first detached from the body A, and the nut F is turned so as to draw the piston to the upper end of the casing. The casing C and the interior of the body A are then filled with soap or shaving-cream, the casing is secured to the body as before, and the cap G is detached, when the brush is ready for use. When the brush is to be used the nut F is turned so as to move the piston E downwards, and thus force a quantity of the shaving-cream through the tubes *a a* among the bristles. The latter are then agitated in a small quantity of water, in such a manner as to dissolve the soap in the water, and thus produce the lather desired, an additional supply of soap being obtained, when required, by moving the piston still further downward.

I am aware that W. S. Jewett obtained a patent on the 10th of April, 1849, for a shaving-brush, in which a piston was so operated as to discharge soap from a hollow handle through tubes into a brush. In this brush, however, the piston travels on a revolving screw projecting into the soap reservoir. The threads of the screw are therefore apt to become clogged with soap, while the latter is discolored by the action of the hard metal of which the screw is made. A feather is also required to prevent the piston from turning with the screw, so that there is considerable friction and wear upon the parts. By securing the piston to a screw travelling in a nut revolving in the upper end of the case, as described, the screw is preserved from contact with the contents of the case, while the screw is protected from injury, when the piston is drawn outward, by the cap G.

I claim as my invention, and desire to secure by Letters Patent—

The arrangement of the case C, piston E, screw *b*, nut F, and cap G, as and for the purpose described.

In testimony whereof I have signed my name to this specification in the presence of two subscribing witnesses.

W. T. WYLIE.
